Specification for Design.

Patented Mar. 9, 1920.

Application filed January 11, 1919. Serial No. 270,745. Term of patent 7 years.

To all whom it may concern:

Be it known that I, JOHN J. WALSH, a citizen of the United States, residing at Brooklyn, in the county of Kings and State of New York, have invented a new, original, and ornamental Design for Letter-Sheets, of which the following is a specification, reference being had to the accompanying drawing, forming a part hereof.

The figure is a plan view of a letter sheet showing my new design.

What I claim is:

The ornamental design for a letter sheet substantially as shown.

JOHN J. WALSH.
